[57] CLAIM

The ornamental design for a control housing for a soldering device, as shown and described.

DESCRIPTION

FIG. 1 is a perspective view of a control housing for a soldering device, showing my new design;
FIG. 2 is a right side elevational view thereof;
FIG. 3 is a top plan view thereof;
FIG. 4 is a rear elevational view thereof;
FIG. 5 is a bottom plan view thereof;
FIG. 6 is a perspective view of a second embodiment of a control housing for a soldering device;
FIG. 7 is an elevational view of the front panel of the second embodiment; and
FIG. 8 is an elevational view of the front panel of the first embodiment.

FIG-1

FIG-2

FIG-4
